CLAIM

The ornamental design for a collapsible work horse, as shown and described.

DESCRIPTION

FIG. 1 is a top perspective view of a collapsible work horse showing my new design;

FIG. 2 is a bottom perspective view thereof;

FIG. 3 is a side elevational view thereof;

FIG. 4 is an end elevational view thereof;

FIG. 5 is a bottom plan view thereof;

FIG. 6 is a side elevational view thereof in collapsed position; and,

FIG. 7 is an end elevational view thereof in collapsed position, the broken lines showing of the hand is for illustrative purposes only and forms no part of the claimed design.
